[57] CLAIM

The ornamental design of a spray actuator and collar, as shown and described.

DESCRIPTION

FIG. 1 is a perspective view of a preferred embodiment of our ornamental design for a spray actuator and collar; FIG. 2 is a top plan view of the spray actuator and collar; FIG. 3 is a side elevational view of the spray actuator and collar;

FIG. 4 is a front elevational view of the spray actuator and collar; and,

FIG. 5 is a rear elevational view of the spray actuator and collar.

The bottom and interior of the spray actuator and collar form no part of the claimed design.
